(57) **CLAIM**

The ornamental design for a fishing lure with curved lip, as shown and described.

DESCRIPTION

FIG. 1 is a perspective view of the fishing lure with curved lip according to the present invention.

FIG. 2 is a front view of the fishing lure illustrated in FIG. 1.

FIG. 3 is rear view of the fishing lure illustrated in FIG. 1.

FIG. 4 is side view of the fishing lure illustrated in FIG. 1.

FIG. 5 is opposite side view of the fishing lure illustrated in FIG. 1.

FIG. 6 is a top view of the fishing lure illustrated in FIG. 1; and,

FIG. 7 is a bottom view of the fishing lure illustrated in FIG. 1.

The surface shading and broken lines shown in FIGS. 1-7 represent portions of the fishing lure with curved lip that form no part of the claimed design.
